United States Patent Office

Des. 188,573
Patented Aug. 9, 1960

188,573

JEEP OR THE LIKE

Norman E. Nelson, Los Angeles, Calif., assignor to Doak Aircraft Co., Inc., Torrance, Calif., a corporation of California

Filed June 18, 1959, Ser. No. 56,421

Term of patent 14 years

(Cl. D71—1)

FIG. 1.

FIG. 2.

FIG. 3.

Fig. 1 is a top plan view of a jeep showing the new design.

Fig. 2 is a side elevational view thereof, the opposite side being the same in appearance.

Fig. 3 is a front elevational view thereof.

I claim:

The ornamental design for a jeep or the like, as shown and described.
